APPARATUS AND METHOD FOR PUNCHING MUSIC SHEETS.

Application filed May 26, 1924. Serial No. 715,889.

This invention relates particularly to the production of music sheets, or music rolls, for use in self-playing musical instruments. In accordance with the invention, a music sheet is prepared by passing a blank sheet in front of a series of punches which are adapted to be rapidly actuated, and the actuation of the punches is controlled by means of the keys and expression devices of a musical instrument, or musical instruments. When any punch is thrown into actuation, it is reciprocated with very great rapidity while the note sheet is fed across its point. In this way, the punch produces a series of overlapping perforations, or, in other words, cuts the paper away, bit by bit, thus producing a slot having comparatively straight edges.

The music sheet thus prepared may be used as a master sheet for preparing any desired number of duplicates, or it may be employed in a self-playing musical instrument for controlling the playing of the instrument, in a known manner.

The accompanying drawings illustrate the manner in which a music sheet may be prepared which is adapted to control the playing of a piano on the one hand, and the playing of a stringed instrument of the violin class on the other hand.

In the drawings—

Figure 1 represents diagrammatically the means whereby, in the playing of an ordinary upright piano, or organ, the playing of the instrument serves to control the operation of punches for translating the music and expression to a music sheet; Fig. 1^a, which may be regarded as an extension of Fig. 1 represents diagrammatically the means whereby the music being played on an electrically controlled stringed instrument by means of the keys of a suitable manual, or console, may be translated to the music sheet undergoing perforation; Fig. 2 represents a broken vertical sectional view of a punch device suitable for the purpose; Fig. 3 is a broken horizontal section taken as indicated at line 3 of Fig. 2; and Fig. 4 is a broken view of the music sheet, this view illustrating diagrammatically the manner in which the playing of a stringed instrument is controlled from the sheet, more particularly with reference to the manner in which a staccato effect may be secured.

Referring first to Fig. 1, A represents the

string-plate of a piano equipped with strings A'; B represents a portion of a piano action having hammers B' and a hammer-rail, or rest, B²; C, the key-manual of the piano, each key serving to actuate a riser C' which operates the jack-butts C², by means of which the hammer is actuated in a well-known manner; D, an expression control being in this case, means for controlling the position of the hammer-rail; E, an expression control, in this case, means for controlling the position of the damper E'; and F, a punch device equipped with punches, the actuation of which is controlled from the keys and expression devices of the piano or other instrument.

In Fig. 1, 1, 2, 3, 4 and 5 denote electromagnets which control the actuation of punches. The punches controlled by these magnets serve to produce the slots 1^b, 2^b, 3^b, 4^b, and 5^b, shown in Fig. 4.

Referring, at this point, to Fig. 1^a, 6, 7, 8, and 9 denote electromagnets controlling the actuation of punches of the punching device F which corresponds with the notes and expression devices of a stringed instrument of the violin class, whose action is diagrammatically shown in Fig. 1^a. The electromagnets, just mentioned, control the actuation of punches designated 6^a, 7^a, 8^a, and 9^a, shown in dotted lines in Fig. 3; and the punches just enumerated serve to produce the slots 6^b, 7^b, 8^b, and 9^b, shown in Fig. 4.

Referring again to Fig. 1, the hammer-rail B² is shown equipped with arms 10 supported on pivots 11, carried by the bracket 12. One of the arms 10 has rigidly connected therewith, or with its pivot, an actuating arm 10^a. The hammer-rail is normally at rest on a support, or stop, 13, carried by the bracket 12. When the hammer-rail is moved toward the strings, it shortens the movement of the hammers, thus producing a softer sound. In practice, provision may be made for moving the hammer-rail to any desired position. In the self-playing piano instrument, it is preferred to make provision for supporting the hammer-rail in at least four different positions, but for simplicity of explanation, such provision is not shown and described in the present application.

The expression device D may be assumed as comprising a pedal 14 connected by a link 15 with a lever 16 supported on a fulcrum

17. The lever 16 is connected by a link 18 with the arm 10^a. One extremity of the lever 16 is connected with a plunger 19 equipped with a piston 20 which works in a dash-pot 21, which is movably mounted, being connected with a guide 22. The dash-pot 21 rests upon a spring 23 upon a support 24. A pedal spring 25 is interposed between this support and the pedal 14.
- 18 Referring to the electric circuits shown in Fig. 1, 26 denotes a positive main, and 27, a negative main. The dash-pot 21 is equipped with a contact member 28 which normally is in contact with a neutral, or 19 non-energized, block 29. A branch conductor 30 connects the contact 28 with the positive main 26. One end of each of the solenoids of the electromagnets, 1 to 5 inclusive, is connected with a negative wire 31.
- 20 The other end of the electromagnet 1 has leading thereto a conductor 32; the electromagnet 2 has leading thereto a conductor 33; the electromagnet 3 has leading thereto a conductor 34; the electromagnet 4 has leading thereto a conductor 35; and the electromagnet 5 has leading thereto a conductor 36.
- 21 The contact member 28 co-acts, on the one hand, with a contact 35^a connected with the conductor 35, and, on the other hand, with a contact 36^a connected with the conductor 36. Thus, the contacts 28 and 35^a control the magnet 4, and the contacts 28 and 36^a control the magnet 5. When the pedal 14 is depressed, it lifts the hammer-rail B² and, at the same time, lifts the piston 20. The dash-pot 21 is filled with fluid so that the sudden lifting of the piston causes the dash-pot to be lifted, thereby moving the contact member 28 into contact with the contact member 35^a. This causes the magnet 4 to be energized, and the magnet 4 controls a punch adapted to cut slots in a music sheet corresponding with the advanced position of the hammer-rail B², so that when the music sheet is used in a self-playing instrument, a softer tone will result. The player may keep his foot on the pedal 14 for the desired length of time in the playing of the piano, but the dash-pot 21 will, nevertheless, return to the normal position shown in Fig. 1, thus breaking the circuit of the magnet 4 after a slot of a certain length has been cut in the music sheet.
- 22 When the player releases the pedal, the spring 25 returns the pedal to its normal position and depresses the piston 20. This causes the dash-pot 21 to be lowered, compressing the spring 23 and carrying the contact member 28 into contact with the contact member 36^a. This closes the circuit of the magnet 5. The magnet 5 controls the actuation of a punch which serves to punch a slot in the music sheet which corresponds with the proper moment for the return of

the hammer-rail to its normal position, speaking now of the self-playing instrument. In practice, the self-playing instrument may be provided with means whereby the hammer-rail, after moving to a certain position nearer the strings will remain in that position until the slot cut by the punch controlled by the magnet 5 serves to restore the hammer-rail to its normal position.

23 Still referring to Fig. 1, the damper E' is normally pressed against the string, as by means of a spring 37, and the actuating device of the damper is equipped with an arm or lever 38 which is adapted to retract the damper. The expression device E which controls the damper may be assumed to comprise a pedal 39 connected by a link 40 with a lever 41 which has one end supported on a fulcrum 42. The other end of the lever 41 is connected by a plunger 43 with a piston 44 located in a dash-pot 45. The dash-pot is guided by a guide 46 and rests on a spring 47 mounted on a support 48. A spring 49 is interposed between the support 48 and the pedal 39. The pedal has an arm 39^a which engages the lower end of the lever 38. The dash-pot 45 is equipped with a contact 50 which is connected by a conductor 51 with the positive main 26. In the normal position of the dash-pot, the contact member 50 engages a neutral block 52. Contact member 50 co-acts with the contact member 33^a connected with the conductor 33 and with a contact member 34^a connected with the conductor 33 and with a contact member 34^a connected with the conductor 34. Thus, the contact members 50 and 33^a control the circuit of the solenoid 2; and the contact members 50 and 34^a control the solenoid 3. When the pedal E is depressed, the contact member 50 is moved into contact with the contact member 33^a, and the solenoid 2 causes a punch to be actuated to cut a slot in the music sheet corresponding with the point of removal of the damper from the string. The dash-pot returns to the normal position shown in Fig. 1, even though the pedal E be held depressed during the proper period of time by the operator. Upon the removal of the foot, the piston 44 is permitted to descend, thus depressing the dash-pot and carrying the contact member 50 into contact with the contact member 34^a. This causes the electromagnet 3 to be energized, thus causing a punch to be operated to cut a slot corresponding with the point of removal of the foot from the pedal. In practice, provision is made in the self-playing instrument, so that the slot will cause the damper to be again applied to the string at this point. The circuit of the electromagnet 3 is broken after a brief interval by the return of the dash-pot 45 to its normal position under the influence of the spring 47.

Each key of the key-manual C is supported on a fulcrum 53, and each key is equipped at its rear end with a circuit closer 54 which is adapted to close circuits at a pair of contact member 55 and 56, the former of which is connected with the conductor 30, and the latter of which is connected with the conductor 32. Thus, when the circuit is closed by the contact member 54, the solenoid 1 is energized. The solenoid 1 controls the actuation of a punch for punching a slot in the music sheet which corresponds with the note struck by the key.

Referring now to Fig. 1^a, G represents the key-manual, or key-board of the console, for controlling a stringed instrument of the violin class, such as a violin.

It is to be understood that the punch device F is equipped with a series of punches corresponding with the notes and various expression devices of the piano, as explained with reference to Fig. 1; and it is to be understood further that the punch device F is equipped with a series of punches corresponding with the notes and expression devices of the electrically operated stringed instrument controlled by the key-manual G.

In Fig. 1^a, H represents a string; I, a rotary bow whose depression into contact with the string is controlled by a bow-magnet I'; J, a finger-lever whose movement into contact with the string is controlled by a finger-magnet J'; K, a motor which serves to rotate the bow; L, a loud pedal, which, when depressed, causes the speed of the motor to be increased; M, a soft pedal, which, when depressed, causes the speed of the motor to be decreased; N, an electromagnet which controls the energizing and de-energizing of the magnet 9, which, in turn, controls the actuation of the staccato punch; O, a shunt magnet which controls the armature of the magnet N; P, a dashpot, or timing device, which controls the downward pull or closing movement of the armature of the magnet O; Q and Q', switches interposed in the circuits, as shown; and R, a resistance element, such as a lamp, interposed in one of the circuits.

It may be stated here, that the electrically operated stringed instrument mechanism herein referred to for the purpose of illustrating the present invention is of a well-known type, in which the bows corresponding with the several strings of the instrument are continuously driven, and in which the depression of a bow and the application of a finger to the string are controlled by a common circuit; and in the illustration here given, the circuit controlling the application of the bow and the finger to the string is controlled by a key, it being understood that the key-manual is provided with a key corresponding with each note and is

provided with a circuit controlled by each key.

The mains 26 and 27, shown in Fig. 1, may be understood as continued in Fig. 1^a. The positive main 26 has a branch 26^a in which the switch Q and resistance R are interposed, and has a branch 26^b in which the switch Q' is interposed. In practice, the feeding of the music sheet in front of the punches commences before the playing of the musical instruments commences, and the switch Q is used to maintain the magnet N in energized condition, and thus prevent the operation of the staccato magnet 9 at any time except when the musical instruments are being played. In this connection, it may be stated here that the staccato magnet operates to cause a slot to be punched in the music sheet only when no key of the manual G is in the depressed position. The purpose is to cut a slot in the music sheet in such position that it may serve to cause the bow to be lifted from the string even though the finger may dwell upon the string.

The negative main 27 has a branch 27^a which is connected with the upper ends of the electromagnets 6 to 9 inclusive, and has a branch 27^b which is provided with sub-branches 27^c and 27^d which connect respectively with the magnets N and O.

The motor K is provided with terminals 57, 58, 59 and 60 which are so connected with the coils of the motor as to enable the motor to run normally at a given speed, or to have the speed increased for producing a louder tone, or decreased for producing a softer tone. The negative branch 27^a has a branch 61 leading to the terminal 58, and has a branch 62 connected by conductors 63, 64, 65 and 66 with the upper ends of the magnets 6 to 9 inclusive.

Each key of the key-manual G controls parallel circuits which include a conductor 67 connected with a punch-controlling magnet, such as the magnet 6; a conductor 68 which includes the windings of the electromagnets J' and I' and which connects with the positive wire 26^a; a contact member 67^a connected with the conductor 67; a contact member 68^a connected with the conductor 68; and a conductor 69 connected with the positive branch 26^b and connected with the contact member 69^a mounted on the rear end of the key and co-acting with each of the contact members 67^a and 68^a, the arrangement being such that when the circuit through the conductor 68 is closed in playing a note, the circuit through the conductor 67 is likewise closed to cause the corresponding punch to be actuated.

The expression device L may be regarded as a pedal adapted to cause the speed of the motor to be increased. This pedal is equipped with a pair of contacts 70 and 71 which are connected by a conductor 72 with

- the positive branch 26^b. The contact 70 co-acts with a contact 73 connected with a conductor 74 which leads to the binding post 59 of the motor. When this conductor is energized, the current passes to the terminal 59 of the motor and through the motor to the terminal 58 and thence to the negative line 61, thus causing the motor to operate at increased speed, giving the loud expression. At the same time, the contact member 71 engages a contact member 75 which is connected by a conductor 75^a with one end of the magnet 7, which controls the actuation of a punch which produces the slots in the music sheet which serve to give the loud expression, as, when the music sheet is employed for automatically controlling the operation of a violin. The expression device M may be regarded as a pedal which is equipped with a pair of contacts 76 and 77 which are connected by a conductor 78 with the conductor 72. The contact member 76 co-acts with a contact member 79 which is connected with a conductor 79^a which leads to the terminal 60 of the motor. When this conductor is energized, current passes to the terminal 60, thence through the motor to the terminal 58 and thence through the negative line 61. At the same time, the contact member 77 makes contact with a contact member 80 connected with a conductor 81 connected with a conductor 80^a which leads to one end of the electromagnet 8 which controls the punch for producing the slots in the music sheet which control the soft expression. The conductor 81 connects the positive branch 26^b with the terminal 57 of the motor. When the conductor 81 is energized, the current passes to the terminal 57, thence through the motor to the terminal 58, back through the negative line 61. This is the circuit for the normal operation of the motor. The positive branch 26^a leads to one end of the series magnet N, and the negative branch 27^c connects with the other end of said magnet. The positive branch 26^b is electrically connected with the armature N' of the magnet N. Said armature carries a contact member 82 which co-acts with a contact member 83 connected with a conductor 83^a which connects with one end of the magnet 9, which controls the staccato punch. The armature N' is equipped also with a contact member 84 which co-acts with a contact member 85 connected by a conductor 85^a with one end of the electromagnet O. The magnet O has an armature O' which is equipped with an extension 86 which engages an extension 87 of the armature N'. The armature O' is also equipped with an arm 88 which is connected with a plunger 89 equipped with a piston 90, said piston being located in the dash-pot P. The piston 90 is equipped with an upwardly opening check valve 90^a. The dash-pot P is filled with fluid, and the piston operates to retard the downward movement of the armature O' when the magnet O is energized. In the position shown in Fig. 1^a, the circuit of the staccato punch is broken at the contacts 82 and 83, while the circuit of the magnet O is closed at the contacts 84 and 85. While the music is being played, and the operation of the punch device is thus being controlled by the playing of the music, the switch Q is open, and the switch Q' is closed. When a key of the manual G is struck in playing a note, current passes from the positive main through the conductor 68 which energizes the finger-magnet J' and the bow-magnet I', and current is thus directed also to the series magnet N. This causes the armature N' to be depressed from the position shown in Fig. 1^a, thus breaking the circuit of the magnet O at the contacts 84 and 85. When the finger is released from the key, the circuit of the magnet N is broken at the contacts 68^a and 69^a, thus permitting the armature N' to fly up. This closes the circuit of the staccato magnet 9 at the contacts 82 and 83 and, at the same time, closes the circuit of the shunt magnet O at the contacts 84 and 85. The magnet O then operates to draw its armature O' downward with a retarded movement, thus bringing the armature N' again to the position shown in Fig. 1^a and breaking the circuit of the staccato magnet. The staccato magnet is thus kept energized for a sufficient period of time to enable a slot of desired length to be cut in the music sheet, which slot serves to give the staccato effect when the music sheet is employed in connection with an automatically played violin. From the foregoing, it will be seen that the staccato magnet can only operate when the finger is released from the key of the manual G, and that the length of the slot cut in the music sheet is automatically controlled by the magnet O and the associated dash-pot, or timing device. Any suitable timing device may be employed as a substitute for the dash-pots shown in the drawings. For example, timing clocks may be employed for regulating the movements which are regulated by the dash-pots. The punch device F may be of any suitable construction. It is desirable, however, to employ a punching machine which is capable of imparting very rapid vibration to any punch when such punch is thrown into operation. In the illustration given, a shaft 86 is rotated rapidly by means of a small motor (not shown). This shaft is equipped with eccentrics 86^a (one shown), which actuate levers 87, which, in turn, serve to impart rapid vibration to a cross-head 88. The punches preferably are arranged in a horizontal row, being mounted in suitable guide

perforations 89 in a cross-bar 90, as will be understood from Figs. 2 and 3. Each punch is equipped with a finger 91 engaged by a lip 92 of the cross-head, by means of which the 5 punch is retracted. A vertically reciprocable actuator-bar 93 is provided for actuating each punch and has its upper end disposed in front of the base end of the punch. The cross-head is provided with a recess 94 10 into which anyone of the cross-bars 93 may be projected, and, when so projected, the bar 93, by reason of the engagement with the shoulder 94^a, will serve to actuate the punch. That is, when the bar 93 is elevated, it causes 15 the reciprocating cross-head 88 to transmit its motion to the punch. Each bar 93 rests, at its lower end, on the rear end of a lever 95 which is connected by a link 96 to the armature 97 of a controlling magnet. For 20 example, the punch 9^a, shown in Fig. 2, is controlled by the staccato magnet 9, the punch being thrown into operation when the armature 97 is depressed. Each punch of 25 the machine is controlled in a similar manner.

The music sheet 98 is taken from a suitable roll (not shown) at the upper end of the machine and is drawn by a pair of feed rolls 99 over a shoe, or die-bar 100, 30 which is equipped with dies 101 which admit the operative ends of the punches when they are in operation. A suitable motor (not shown) is provided for causing the music sheet 98 to be fed across the die-bar 100 at a suitable speed.

In Fig. 4, 98^a represents a section of the music sheet allotted to the piano, and 98^b represents a section allotted to the stringed instrument. In a general way, the manner 40 of using a music sheet in connection with a self-playing instrument is well understood in the art, and a brief description with reference to Fig. 4 will suffice. The music sheet is placed over a metallic tracker-bar, 45 or roll, 102, and is interposed between said tracker-bar and the contact members which are designated 1^c, 2^c, 3^c, 4^c, and 5^c, in the left-hand portion of Fig. 4, and 6^c, 7^c, 8^c, and 9^c, in the right-hand portion of Fig. 4. 50 The manner in which the staccato control is effected in connection with a stringed instrument of the viol class is illustrated in Fig. 4. The string is designated H', the bow-magnet is designated I², and the finger-magnet is designated J². It is to be understood that the bow, designated I³, is constantly rotated by means of a motor (not shown). A positive conductor 103 has in 60 its course the solenoids of the magnets I² and J² and connects with the contact member 6^c which co-acts with the row of note-slots 6^b. When such a slot is under the contact 6^c, the circuit is completed through the tracker-bar 102 and a return, or negative, 65 line 104. A branch 103^a of the positive line

103 has in its course the solenoid of a switch-controlling magnet 105, and the conductor 103 connects with the staccato contact 9^c. When one of the staccato slots 9^b is under the brush, or contact, 9^c, a circuit 70 is completed through the tracker-bar and the return conductor 104. This energizes the magnet 105 causing it to attract the armature 106, thus closing a switch 107 interposed in a shunt line 108, which short-circuits or cuts out the bow-magnet I², thus causing the bow to be lifted wholly from the string. When the slot 9^b passes from beneath the brush 9^c, the circuit of magnet 105 is broken, permitting the armature 106 75 to drop, thus breaking the shunt circuit through the conductor 108 and leaving the bow-magnet I² in condition to operate again when a note is sounded.

It is to be understood, with reference to Fig. 1^a, that each key of the key-manual G is provided with suitable electrical connections similar to those shown in Fig. 1^a and including wires connected with the wires 26^a and 85^a, whereby each key will control the electro-magnets N and O which control the staccato punch. Thus, each key would have a conductor 69 connected with the branch 26^b and a conductor 68 extending through solenoids of the electromagnets J' 80 and I' and to the conductor 26^a so that each key would control the staccato punch through the medium of the electromagnetic device comprising the magnet N and the magnet O. When any key of the manual is 85 depressed, the staccato punch cannot be operated, but when the keys are all in the open position, the staccato punch will operate. As has been stated, prior to the beginning 90 of the playing operation, and while the note-sheet is travelling across the dies, the switch Q is closed, thus energizing the magnet N and preventing operation of the staccato punch. This expedient is employed 95 also when it is desired to have the music sheet travel idly, as where a space is provided between different pieces of music on the same music roll, or where a pause occurs 100 in the music for any considerable period.

It will be understood from the description given, that the keys and expression devices of a musical instrument of the piano or organ type, may, by equipment of the character shown in Fig. 1, be caused to control the punching of a music sheet to reproduce the music and expression on the sheet as the musical instrument is played; also, that a stringed instrument of the viol class whose operation is controlled from a key-manual may, by means of the equipment 110 illustrated in Fig. 1^a, be made to control punches for reproducing the music and expression in the music sheet as the stringed instrument is played. These instruments 115 may be played in synchronism, and the 120 125 130

music and expression played on each instrument reproduced on a common music sheet. The music sheet thus produced, whether by the playing of one instrument or two, may be employed as a master music sheet to produce duplicates to be used in controlling the automatic playing of similar musical instruments; or, if desired, the music sheet produced by the means herein described may be employed directly for controlling the operation of a self-playing instrument.

The foregoing detailed description has been given for clearness of understanding only, and no unnecessary limitations should be understood therefrom, it being the intent to claim therein all of the invention disclosed, in view of the prior art.

What I regard as new, and desire to secure by Letters Patent, is:

1. In combination, a musical instrument of the piano, or organ, type, equipped with a key-manual, a stringed instrument of the viol class, a key-manual controlling the playing of the notes of said stringed instrument, a machine equipped with a plurality of punches, electromagnets controlling the operation of said punches, and contacts actuated by the keys of said manuals and controlling the circuits of said electromagnets.

2. In combination, a machine equipped with a plurality of punches, and a musical instrument equipped with keys controlling the actuation of certain of said punches and equipped with a manually operated expression device controlling the actuation of one or more of said punches, said expression device being equipped with timing means for controlling the period of actuation of the corresponding punch.

3. In combination, a musical instrument of the piano, or organ, type, equipped with a key-manual and equipped with a manually operated expression device, a machine equipped with a plurality of punches, means controlled by each key for controlling the operation of a corresponding punch, and means associated with said expression device for controlling the operation of two or more of said punches.

4. In combination, a machine equipped with a plurality of note-punches and a plurality of expression punches, electromagnets controlling the operation of the punches, and a musical instrument having keys equipped with circuit controlling devices controlling the electromagnets which control the actuation of the note-punches, and having a manually operated expression device equipped with a contact device which controls the circuits of the electromagnets of two expression punches.

5. In combination, an electrically operated stringed instrument of the viol class, a key-manual controlling the playing of the notes

of said stringed instrument, a machine equipped with a plurality of note-punches and with a staccato punch, an electromagnet associated with each key and controlling the actuation of a note-punch and having a circuit controlled by the corresponding key, a staccato magnet controlling the actuation of said staccato punch, said last-mentioned magnet having a normally open circuit provided with a contact, and an electromagnetic device associated with the note-playing circuit controlled by a key of the key-manual, said electromagnetic device being operative to close the circuit of the staccato magnet only when the key is in the open position.

6. In combination, an electrically operated instrument of the viol class, a key-manual provided with a key corresponding with each note, note-sounding means, including a circuit associated with each key, such circuit having a switch operated by the key, a machine equipped with a plurality of note-punches and with a staccato punch, a note magnet controlling the actuation of each note punch, a staccato magnet controlling the actuation of a staccato punch, a circuit for each note magnet controlled by a corresponding key, and an electromagnetic device controlling the circuit of the staccato magnet, said device comprising an electromagnet in series with the magnets of the note-sounding means and equipped with an armature controlling the circuit of the staccato magnet, and a second electromagnet having an armature controlling said first-mentioned armature and having a circuit controlled by said first-mentioned armature.

7. In combination, an electrically operated instrument of the viol class, a key-manual provided with a key corresponding with each note, note-sounding means, including a circuit associated with each key, such circuit having a switch operated by the key, a machine equipped with a plurality of note-punches and with a staccato punch, a note magnet controlling the actuation of each note punch, a staccato magnet controlling the actuation of the staccato punch, a circuit for each note magnet controlled by a corresponding key, and an electromagnetic device controlling the circuit of the staccato magnet, said device comprising an electromagnet in series with the magnets of the note-sounding means and equipped with an armature controlling the circuit of the staccato magnet, a second electromagnet having an armature controlling said first-mentioned armature and having a circuit controlled by said first-mentioned armature, and a timing device controlling the closing of the armature of said second electromagnet.

8. In combination, a stringed instrument of the viol class, a key-manual provided with a key for each note, a bow, a bow-motor having circuits for varying speeds, a bow-

magnet and a finger-magnet arranged in series and associated with each key, means carried by the key controlling the circuit of said magnets, a punching machine provided with a plurality of note-punches and with a staccato punch, a note magnet controlling the actuation of each note-punch, a staccato magnet controlling the actuation of the staccato punch, a circuit controlled by each key and controlling the corresponding note magnet, expression devices equipped with circuits controlling the speed of the motor, and an electromagnetic device controlling the staccato magnet, said electromagnetic device being controlled from the keys of said manual and being operative to close the circuit of the staccato magnet only when all of said keys are in the open position.

9. In combination, a stringed instrument of the viol class, a key-manual provided with a key corresponding with each note, note-sounding means equipped with a circuit, such note-sounding means being associated with each key and equipped with a circuit controlled by such key, a punching machine provided with a plurality of note punches and with a staccato punch, note magnets controlling the actuation of the note-punches, a staccato magnet controlling the

actuation of the staccato punch, circuits for the note magnets controlled respectively by the corresponding keys, and an electromagnetic device controlling the circuit of the staccato magnet and including a master magnet which directly controls the circuit of the staccato magnet, and which has a circuit controlled by each of said keys and controlled also by a main switch, whereby the master magnet may be energized to prevent actuation of the staccato punch during periods when music is not being played.

10. The method of producing a music sheet which comprises controlling the actuation of a note-punch by each of the key-manual of the musical instrument and controlling the actuation of a plurality of expression punches by a single expression device of the musical instrument.

11. The method of producing a music sheet adapted for controlling the playing of a stringed instrument of the viol class which comprises the controlling of a note-punch by each key of a key-manual and the controlling of a staccato punch by each of said keys in such manner that the staccato punch will be actuated only when the keys are in open position.

BERTIE E. MILLS.
